UNITED STATES PATENT OFFICE.

JOHN B. WEEKS, OF HANOVER, PENNSYLVANIA, ASSIGNOR TO LONG FURNITURE COMPANY, OF HANOVER, PENNSYLVANIA, A CORPORATION OF PENNSYLVANIA.

PHONOGRAPH CABINET.

Application filed November 8, 1922. Serial No. 599,648.

To all whom it may concern:

Be it known that I, JOHN B. WEEKS, a citizen of the United States, residing at Hanover, in the county of York and State of Pennsylvania, have invented new and useful Improvements in Phonograph Cabinets, of which the following is a specification.

This invention relates to improvements in phonograph cabinets.

10 The object is to provide an attachment for installation in cabinets built for use in connection with the portable type of talking machines, wherein the said cabinet completely encloses said machine, and has the appearance of one of the expensive, built-in or floor cabinet machines.

Another object is to provide such an attachment which is adapted to close the space surrounding the portable talking machine 20 at the front portion of the cabinet, and thus provide a continuous, uninterrupted passage for the sounds emanating from the machine and improving the quality and the volume of tones, the said attachment having the further advantage of concealing the base of the machine and generally enhancing the appearance of the combination.

A full and complete understanding of the 30 invention may be obtained from a consideration of the following detailed description, taken in connection with the accompanying drawings forming a part of this specification, it being understood that while the drawings show a practical form of the invention, the latter is not to be confined to strict conformity with the showing thereof, but may be changed or modified, so long as such changes or modifications mark no material departure from the salient features of 40 the invention, as specifically pointed out in the appended claims.

In the drawings, in which similar reference characters designate corresponding parts throughout the several figures:

45 Figure 1 is a perspective view of the right hand portion of a cabinet built to receive a portable talking machine and showing how the base portion of the latter is exposed to view without the use of the improved attachment of the present application;

Figure 2 is a similar view showing the present invention in position;

Figure 3 is a transverse sectional view through the talking machine compartment of the cabinet, the machine being shown 55 partly broken away to illustrate the interfitting relation of the attachment with the cabinet and the machine;

Figure 4 is a horizontal sectional view through the machine compartment of the 60 cabinet, parts being broken away to further illustrate the position of the attachment;

Figure 5 is a detail perspective view of the attachment.

The invention of this application is an 65 improvement on the invention disclosed in my prior Patent No. 1,410,977, dated March 28th, 1922.

The drawings illustrate, in accordance with the subject matter of said patent, a 70 cabinet of the so-called floor type or cabinet type, wherein are built a talking machine compartment 1, to the side of which is located a record compartment, generally of 75 equal size and capacity, access being had to the latter by means of a swinging front door 3, the stationary top 4 of the same being generally utilized as a table or support. The record compartment may be equipped with 80 the usual shelves or with vertical stalls for the reception of the disc records.

The machine compartment 1 is provided with a hinged top 5 swingable upwardly and rearwardly to change the records and adjust 85 the machine in the usual manner, the rear of said compartment being closed by a stationary wall 6, preferably screwed in position and adapted to be removed when introducing or removing the talking machine 7.

The said machine rests on front and rear 90 cleats 8 and 9 respectively which may be changed or shifted to receive and properly support the different makes of machines and the said compartment 1 is provided at the upper portion of its open front with a front 95 wall or panel 10 rigidly secured in place and adapted to conceal the upper portion of the front of the talking machine, and to provide an outlet below the same for sounds coming from between the slats 11 thereof, said 100

slats being either stationary or adjustable as desired. The front door 12 is preferably hinged to the outer vertical side edge of the cabinet, and is adapted to be swung wide open, as shown in Figure 1, to avoid obstructing the passage of the sounds.

As thus far described, the cabinet is substantially the same as that disclosed in the aforesaid patent, and it will be seen, upon reference to Figure 1, that such a structure betrays the nature of the machine inclosed therein, by disclosing the base of the same through the opening below the front panel or wall 10, the front supporting strip or cleat 8 being in full view, when the door 12 is opened as well as the base and leg portions of the machine.

By reason of the space between the walls or sides of the machine compartment 1 and the sides of the machine, the quality and volume of the tones or sounds coming from the front of the machine are impaired, and the object of the present invention is to eliminate these breaks in the passageway so as to provide a continuous passage by covering these spaces and exposing to view only the tone outlet of the machine, as shown in Figure 2 of the drawings.

The attachment comprises a front panel 13 preferably formed of laminated wood having its grain running in different directions to provide strength and lightness, the said panel having a central, rectangular opening 14, equal in length with the space between the side walls of the talking machines, and in height to the combined spaces between the sound regulating slats 11. This rectangular opening 14 is provided with rearwardly extending side walls 15 suitably secured to the rear face of the front panel 13, and have their rear free edges 16 bevelled to snugly fit the ordinarily bevelled or beaded front edges of the side walls of the machine, so that a continuous side wall is formed to permit an uninterrupted outflow of the sounds or tones from the machine. A rearwardly extending top wall or strip 17 is preferably secured to the rear face of the front panel 13, and the rear edge of the same is adapted to fit against the front face of the machine and form a continuation of the top or roof of the sound chamber of the machine. This strip or wall is not essential. The lower edge of the opening 14 is preferably flanked by a horizontal wall or strip 18 having its upper surface flush with the surface of the bottom wall 19 of the machine. The side walls 15 of the attachment are preferably reinforced by wooden fillets 20, and it will be seen that the top, bottom and side walls are of different widths to extend to and fit against the front of the talking machine to provide a continuous passage for the sounds, and to act as a brace to steady the machine within

the compartment, and to permit of readily moving the cabinet from place to place without disturbing the proper position of the machine.

The ends of the front panel 13 extend sufficiently beyond the side walls 15 to reach to the inner faces of the side walls of the compartment, and are adapted to receive brads, nails or screws 21 to hold the attachment in place within the compartment 1, said brads entering the rear faces of a central strip or post 22, and a corner strip 23 respectively, said strips comprising portions of the structure of the cabinet, as clearly shown in Figure 4 of the drawings.

From the foregoing it will be seen that a simple, cheaply manufactured and easily installed attachment has been provided, which may be incorporated in the structure of cabinets for holding ordinary types of portable talking machines, the said attachment providing a continuous conduit or passageway for the sounds produced by said machine, and acting as additional bracing or steady means for the machine, while concealing the base portion thereof to further enhance the effect of a built-in combination.

What is claimed is:—

1. An attachment for phonograph cabinets having a compartment for a portable machine comprising a front panel adapted to fit within the sound outlet of said cabinet, said panel having an opening co-extensive with the sound outlet of the machine, and rearwardly extending walls surrounding said opening and adapted to abut against the front of the talking machine to form a continuous sound outlet passage.

2. An attachment for portable talking machine cabinets comprising a wooden frame adapted to be secured in the sound outlet of the cabinet to cover the base of the talking machine, said frame having a front panel provided with a rectangular opening co-extensive with the sound outlet of the machine, and walls extending rearwardly from the panel at the margins of said opening and adapted to contact with the corresponding portions of the front of the machine to form a continuous sound outlet passage, said panel having its ends secured to the rear faces of the central and end posts of the cabinet and giving the appearance of a built-in phonograph cabinet.

3. The combination with a cabinet having a compartment of a sufficient size to receive a talking machine, said compartment having an open front and an open back, the machine being inserted within the compartment through the open back, a front wall extending across the top of the open front, and a door for closing the open front of the herein-described attachment, comprising a front panel fitting flush within and filling the

space at the open front below the front wall, said panel having a central opening of a size and shape to expose the slats of the talking machine, and strips extending inwardly from the panel at the said opening and engaging with the front of the talking machine, said strips defining a passage for the musical sounds issuing from the machine.

In testimony, that I claim the foregoing 10 as my own, I have hereto affixed my signature.

JOHN B. WEEKS.
